(57) **CLAIM**

The ornamental design for an electronic limited slip differential with separation of clutch and actuator, as shown and described.

DESCRIPTION

FIG. 1 is a front perspective view of a first embodiment of an electronic limited slip differential with separation of clutch and actuator showing the new design.

FIG. 2 is a front view of the first embodiment of the electronic limited slip differential with separation of clutch and actuator of FIG. 1.

FIG. 3 is a rear view of the first embodiment of the electronic limited slip differential with separation of clutch and actuator of FIG. 1.

FIG. 4 is a first side view of the first embodiment of the electronic limited slip differential with separation of clutch and actuator of FIG. 1.

FIG. 5 is a second side view of the first embodiment of the electronic limited slip differential with separation of clutch and actuator of FIG. 1.

FIG. 6 is a third side view of the first embodiment of the electronic limited slip differential with separation of clutch and actuator of FIG. 1; and,

FIG. 7 is a fourth side view of the first embodiment of the electronic limited slip differential with separation of clutch and actuator of FIG. 1.

Any portion of the electronic limited slip differential with separation of clutch and actuator shown in broken lines is for the purpose of illustrating environmental structure and forms no part of the claimed design.
